UNITED STATES PATENT OFFICE.

SOLOMON D. GUGGENHEIM, OF CLEVELAND, OHIO.

IRONING-PRESS.

1,141,184.

Specification of Letters Patent.

Patented June 1, 1915.

Application filed September 26, 1910. Serial No. 583,790.

To all whom it may concern:

Be it known that I, SOLOMON D. GUGGENHEIM, a citizen of the United States, residing at Cleveland, in the county of Cuyahoga and State of Ohio, have invented certain new and useful Improvements in Ironing-Presses, of which the following is a specification.

This invention relates generally to ironing machines, and is more particularly designed as an ironing press for the bosoms of shirts and waists.

More specifically the invention relates to an ironing press comprising an internal ironing member preferably mounted in a stationary position and provided with a yoke ironing plate under one end and forming substantially a line corresponding to the shoulder folding line of a shirt or waist, together with a yoke ironing member movably mounted and coöperating with the yoke ironing plate and an external bosom ironing member adapted to move in the sector of a circle toward and from the surface of the internal ironing member and when closed to be pressed tightly against such internal ironing member to bring about the pressing of the bosom of the shirt or waist.

The invention also relates to certain arrangements of certain features in connection with the internal ironing member and the ironing plate, whereby the box plait of shirts or waists may be ironed to cause them to stand up properly and whereby the embroidery on these box plaits may be caused to appear raised from the material.

The invention may be further briefly summarized as consisting in the construction and combination of parts hereinafter set forth in the following description, drawings and claims.

Referring to the drawings, Figure 1 is a side elevation of the machine; Fig. 2 is a front elevation with the ironing cloth for the internal ironing member broken away to show the parts; Fig. 3 is a top plan view; Fig. 4 is a side elevation partly in section showing the ironing members enlarged and with parts broken away; Fig. 5 is a top plan view of the main portion of the collar former with the top plate removed; Fig. 6 is a top plan view of the same parts with a portion of the cover plate applied showing the operating devices above the plate; Fig. 7 is a front end elevation of the collar former; Fig. 8 is a section upon the line 8—8 of Fig.

5; Fig. 9 is an enlarged sectional view of the yoke ironer with portions of the adjacent parts in section; Fig. 10 is a rear elevation of the yoke ironer; Fig. 11 is a sectional view through the main body portion of the external and internal ironing members; Fig. 12 is a front elevation of a modification showing the ironing plate employed in ironing the bosoms of fancy waists; Fig. 13 is a transverse section of the ironing members with the ironing plate shown in Fig. 12 in place; Fig. 14 is a side elevation of a portion of the machine showing a modified form of gear frame shifting mechanism; and Fig. 15 is a rear elevation of the same.

In carrying out the invention any suitable frame 1 is provided with an upper horizontal plate 2 upon which is secured an internal ironing member 3 having a cavity 4 therein to which live steam is supplied by means of a suitable pipe 5. A pipe 6 leads from this chamber and carries off the water of condensation. The upper surface of this internal ironing member 3 is preferably curved transversely, as shown in Figs. 2, 11 and 13, and it is provided at its rear end on the underside with a curved face 7 which is adapted to conform to the general configuration of the yoke in the back of a shirt or waist, and this face tapers off to form an edge 8, shown in Figs. 3 and 10, and corresponding to the folding line of the back of a shirt or waist. This internal ironing member is further provided with a central longitudinally disposed groove 9 adapted to receive suitable padding 10 against which the box-plait or button and button-hole strips are to be pressed. Padding 11 is arranged upon the surface of the internal ironing member and is held in place by any suitable ironing cloth fastened to suitable pins 12 arranged around the edge of this internal ironing member. This ironing cloth is further held in place by a frame member 14 extending upon either side and across the front of the internal ironing member, and it has notches 15 cut in the lower edge for receiving the pins 12. A pin 16 may be secured in each side of the ironing member and upon these pins 16 the frame 14 may be swung. Secured to the yoke ironing face 7 is an ironing plate 17 which is preferably of a polished material for forming a proper ironing surface and the edge of this member coincides with the back edge of the ironing member.

Mounted in suitable openings 18 near the back or shoulder end of the internal ironing member are pins 19, shown in Fig. 7, provided with spacing shoulders 20 and supporting the collar former, shown in detail in Figs. 5 and 6 and shown applied in Figs. 3, 9 and 10. This collar former is provided with a longitudinally disposed groove 22 for receiving the pin 19 which is located at substantially the longitudinal center of the main ironing portion and serves to guide the main body portion 21 so that it moves in a longitudinal direction with respect to the internal ironing member. This main body portion is further provided upon its upper and lower surfaces with diagonally disposed grooves 24, an upper and lower groove being arranged on either side of the center, as shown in Fig. 7. Each pair of grooves receives upper and lower guiding members 25 and 26 respectively of a foot portion 27 which has its back edge arranged transversely of the internal ironing member and its outer corner rounded, as shown in Figs. 5 and 6. Each of these foot portions is provided with a slot 28 arranged parallel with the back edge. The upper guiding members 25 of each of these foot portions 27 is provided upon its inner edge with gear teeth 29 forming a rack and the gear teeth of the two racks mesh with two intermeshing gears 30 and 31 mounted in the casing whereby upon the movement of one of the gears the two foot portions will be forced diagonally to the rear with respect to the main body portion. Secured to one of the gears is a ratchet wheel 32 which is held in any position by a spring-pressed pawl 33 mounted upon a shaft 34 secured in the casing. A thumb piece 35 is secured to the shaft of one of the gear wheels preferably the gear 31, for manipulating the gears and an operating lever 36 or other similar device is secured to the pin 34 for throwing the pawl 33 into and out of engagement with the ratchet wheel 32. A cover 37 is secured upon the main body portion, the thumb piece 35 and lever 36 being arranged above the cover. The slots 28 of the foot portions 27 engage over the pins 19 which are mounted in the plate and upon either side of the center, as shown in Fig. 7. This collar former is located upon the pins 19 secured in the rear or neck end of the internal ironing member in a manner such that its back edge which is transverse with respect to the internal ironing member is coincident with the neck edge of the internal ironing member, so that the folding line of the shirt extends from the back straight portion of this collar former toward the arm holes of the shirt or waist. The adjustable feature of the foot portions 27 is such that any shirt may be applied to the internal ironing member so that its front or bosom may rest flat upon the same and irrespective of the size of the collar band. After the collar band of a shirt has been placed upon the band former the rest of the shirt may be laid down upon the internal ironing member and stretched tightly upon the same.

Coöperating with the yoke ironing plate 17 is a yoke ironer comprising a cast hollow yoke ironing member 38 having suitable bearing portions 39 for receiving a front axle 40 and a rear axle 41, both of these axles being provided with suitable wheels 42 which engage in grooves 43 of a suitable supporting member 44 carried by the frame. The axle 40 is provided with a transverse opening for receiving the reduced end 45 of a shifting rod 46. This reduced end 45 is provided with a nut 47 and a washer 48, and between this washer and the washer 49, arranged against the axle 40, is a spring 50. This arrangement forms a yielding connection between the rod 46 and the yoke ironing member 38 when the latter is moved to the left, as shown in Fig. 9, or toward the yoke ironing plate 17. This rod 46 is connected to the end of the lever arm 51 mounted upon a shaft 52 provided with a suitable operating lever 53 having a pawl 54 engaging a shoulder carried by a member 55 rigid with the frame, whereby the yoke ironing member may be held tightly against the yoke ironing plate 17. The yoke ironing member has a surface portion 56 which is substantially of the shape and configuration of the ironing plate 17 and upon this surface is a suitable padding 57 held in place by a yoke ironing cloth 58 secured to pins 59 arranged around the edge of the yoke ironing member 38. A heating medium is supplied to and exhausted from the cavity 60 in the yoke ironing member through pipes 61 and 62.

A suitable ironing plate mechanism is provided for the machine, and it consists of an ironing plate 63 curved transversely, as shown in Figs. 2 and 11, and it is provided at the neck end with a collar band opening 64, shown in Fig. 3, and with rearwardly extending portions 65 projecting beyond the rear of the neck band former and there secured to laterally extending trunnions 66 which are mounted in eyes 67 carried by rods 68 passing into sockets 69 secured to a transverse shaft 70 provided with an upwardly bent shifting arm 71. The rods 68 are slidable in the sockets 69 so that after the plate 63 is lowered upon the work and the shifting arm 71 is manipulated so as to draw the edge of the plate at the neck band recess against the neck band former, these rods will play in and out of the sockets and permit the movement of the plate without raising the same, a feature which is quite obvious from the construction. The arrangement of this plate is such that it may be

swung upward from the internal ironing member or from the bosom of the shirt, or may be lowered upon the same after it is in its upper position, and further when it is lowered upon the shirt bosom it may be moved inwardly so that the edge of the plate adjacent the neck band opening is brought closely against the neck band former, as shown in Fig. 3, so that the entire bosom of the shirt or waist may be properly ironed even near the edge of the collar band.

The pressing mechanism will now be described. Secured to the frame 1 are forwardly extending brackets 72 each of which is provided with a bearing 73 having an open-ended slot 74 therein which forms a socket for receiving trunnions 75 of the external ironing member 76 which is provided with a cavity 77 therein connected by suitable ports 78 with openings 79 in the trunnions. These openings may be connected with suitable pipes for supplying and exhausting the heating medium. The external ironing member is curved transversely on its underside and has a U-shaped recess 80 conforming somewhat to the configuration of the collar band but extending away from the collar band former sufficiently to allow for its adjustment for any size of collar band.

The external ironing member 76 is provided with an upwardly extending portion 81 having on each end thereof an upwardly extending ear 82 with a substantially flat bearing surface 83 between the ears 82. Secured in the ears 82 are pins 84 which pass through ears 85 carried by a pressure link 86 which is provided with a rounded surface portion 87 adapted to coöperate with the flat face portion 83 in exerting the downward pressure so that the pressure exerted by this link is not brought to bear upon the pins 84. The upper end of this link is provided with a bearing portion 88 mounted on a shaft 89 secured in side frame members 90 and 91 secured together at the top by a cross frame member 92 by means of a bolt 93. The lower ends of these side frame members are mounted upon a transverse shaft 94. Intermediate the upper and lower ends of these side frame members is a transverse shaft 95 upon which is pivoted a pair of links 96 which are pivoted to a crank pin 97 mounted near the periphery of a driving gear 98 mounted upon a suitable shaft 99.

The operation of the foregoing mechanism is such that upon a counter clockwise rotation of the driving gear 98 the links 96 will cause the operating frame members to be swung about the shaft 94 to the rear causing the raising of the external ironing member 76 which will assume a position slightly to the rear of a vertical line passing through the axis of the trunnions of this external ironing member. The operator may then

place the article to be ironed upon the internal ironing member, and after the neck band former has been adjusted to the neck band the ironing plate has been lowered and adjusted on the shirt or waist bosom, the external ironing member may be again lowered into position and pressure exerted thereon by straightening the toggle link 86 when intense pressure will be brought to bear upon the bosom of the shirt or waist, the heat which is applied to these parts bringing about the ironing operation.

The mechanism for bringing about the rotation of the gear 98 consists of a main driving shaft 100 mounted in suitable bearings in the frame and having upon it a pinion 101, shown in dotted lines in Fig. 1, and meshing with a pinion 102, also shown in dotted lines in Fig. 1, and further meshing with an intermediate pinion 103, the latter being in mesh with the pinion 104, the latter, when in proper position, being adapted to mesh with the gear wheel 98. The pinion 102 is also adapted, when in proper position, to mesh with the gear wheel 98. These pinions 102, 103 and 104 are mounted in a suitable frame 105 swung upon the shaft 100 and having a downwardly extending arm 106 provided with a pin 107 extending from one side thereof. This arm is arranged in a manner such that it swings by gravity into a position such that the pinion 102 and pinion 104 are both out of engagement with the gear 98. The pinion 102 is for transmitting the drive in one direction, while the pinion 104 is for transmitting the drive in the opposite direction.

The mechanism for throwing the pinions 102 and 104 into engagement at the proper time comprises a hand lever 108 mounted on a suitable shaft 109 secured to the frame and connected to an operating lever 110, shown in dotted lines in Fig. 1. This lever is connected to a shifting bar 111. This bar 111 is provided with a notch or slot 112 for engagement with the pin 107 and is still further provided with gravity pawls 113 and 114 having suitable stop pins 115 for holding them normally in the position in which the right-hand dog 114 is shown in Fig. 1. These dogs are spaced at a distance from each other and they coöperate with two rotary dogs 116 and 117 mounted in a bracket 118 secured to the frame. These rotary dogs are provided with gear teeth which intermesh whereby a rotary motion conveyed to one is transmitted to the other. These rotary dogs 116 and 117 are provided with shoulders 119 and 120 respectively. One of these dogs is further provided with a pin 121 engaging in a notch 122 in a lever 123 pivoted in a bracket 124 secured to the frame. The upper end of this lever is provided with inclined edge faces 125 and 126 which are adapted to be engaged by friction

rollers 127 and 128 which are arranged upon the side face of the driving gear 98. The friction roller 128 is mounted near the crank pin 97 of the link 96, while the other is 5 diametrically opposed to it.

Assuming that the parts are in the position shown in Fig. 1 after the ironing operation and after the operator has shifted the hand lever 108 into the position shown, 10 power is being transmitted to the driving gear 98 and the friction roller 128 is moving in a counterclockwise direction toward the edge face 126 of the lever 123. Upon the first movement of this gear wheel 98, 15 however, the edge face 125 is released from engagement with the friction roller 127 when the lever 123 shifts slightly in a counter clockwise direction causing the rotary dog 116 to rotate in a clockwise direction, 20 and the rotary dog 117 to rotate in a counter clockwise direction, with the result that the shoulder 120 of the rotary dog 117 passes by the nose of the dog 113 when the latter will move above the shoulder 120. This 25 position of the parts just described remains until the roller 128 engages the edge face 126 of the lever 123 when the latter is shifted in a clockwise direction, causing the shoulder 120 to engage the nose of the dog 30 and raise the bar 111 so that the pin 107, arranged on the arm 106 of the gear frame, is released from the notch 112, in the bar, when the gear frame will shift by gravity in a clockwise direction, causing the gear pinion 102 to disengage from the teeth of 35 the driving gear 98. When the parts are in this position and the ironing member 76 has been raised from the work, the machine is ready for another operation, and this is 40 brought about by shifting the hand lever 108 to the front slowly until the notch 112 in the bar 111 engages the pin 107 when upon further movement of the lever the gear frame 105 will be shifted farther in a 45 clockwise direction bringing the pinion 104 into mesh with the driving gear 98 when the latter will rotate in a clockwise direction to cause the ironing member 76 to be brought 50 into engagement with the work. As soon as it assumes a pressing position upon the work, however, the roller 127 engages the lever 123 and causes the raising of the bar 111 in a similar manner to that already described when the driving mechanism is 55 thrown out of operation and the machine remains in closed position.

In order to hold the front portions of the shirt or waist down upon the ironing portion, a loop 129 of string is provided and it 60 passes over the internal ironing portion and is connected to a spring 130 attached to a hook 131 secured to the frame.

In using the machine for ironing fancy waists, the longitudinal recess 9 of the internal ironing member may be provided

with a padding strip 132 against which the box plait having the embroidery or fancy work is pressed. In case it is desirable not to iron the waist directly against the chest with the padding 132 in the recess, side 70 plate portions 133 may be utilized on each side of the recess 9, and each of these plates is provided with a downwardly extending flange 134 and the padding is arranged between these flanges. These plate portions 75 133, however, if used, are provided with smooth surfaces for ironing the inner surface of the bosom. In place of the plate 63, however, another plate 135 is used, and it is provided with trunnion members 136 upon 80 which it may swing and similar in all respects to the trunnion members of the plate 63. Upon the surface of this plate and on each side of the trunnion members is a suitable padding 137 which is for engagement 85 with the outer surface of the bosom. At the center between the strips of padding 137 is a box-plait ironing plate 138 which is provided with a finished surface for ironing the box-plait or button strip. In ironing 90 fancy waists with the mechanism just described, the operator places the article upon the internal ironing member and upon the lower ironing plate 133 in the same manner in which the waist or shirt is placed upon 95 the machine in the other embodiment. Then the plate 135 is lowered upon the bosom, and the external ironing member operating mechanism is set in motion to cause the ironing members to close upon the bosom when 100 the heat of the parts will strike through the article operated upon and the embroidery or other fancy work upon the waist will be raised or embossed, as it were, from the body of the garment.

In lieu of the mechanism applied to the end of the bar 111 for controlling the shifting of the frame 105, I have provided another form of mechanism which I may employ, and this mechanism is shown in 110 Figs. 14 and 15 and will be described in detail.

In place of the bar 111 a bar 140 is employed, and it is provided with a notch 141 which engages a pin 142 mounted between 115 two extensions 143 and 144 which are continuations of the side plate of the frame 105 and serve to guide the bar 140 which slides freely between the same upon the pin 142. The bar is extended beyond the frame as in 120 the other construction, but in place of the pawls it is provided with a long recess 145 which co-operates with suitable lifting mechanism to be described. It will be seen from the foregoing that when the bar is shifted to the right from the position shown in Fig. 14, it is free to drop upon the pin 142 when 125 it will shift the frame 105 in a manner similar to that already described.

The mechanism for releasing the bar 140 130

from the pin 142 and for permitting it to drop onto said pin comprises a cast plate 146 secured to the rear end of the frame and having mounted thereon suitable guides 147 and 148 and slide bars 149 and 150 which are connected by a lever 151 fulcrumed at its center upon a pin 152. The bar 149 is extended above the lever 151 and is provided with a laterally extending arm 153 which extends over into the path of the pins 127 and 128 carried by the driving gear 98. The slide bar 150 is provided with an inwardly extending foot portion 155 which extends under the lower edge of the bar 140; while the slide bar 149 is provided with a reversely turned foot portion 155 also extending under the bar 140 at all times, and their operation will now be described. When the parts are in the position shown in Fig. 14, the machine is at rest with the ironing members closed and when the operator desires these members to open, the bar 140 is shifted to the rear by mechanism already described, so that the end portion 25 of the lever drops over the edge of the foot portion 154 of the slide bar 150 which at this particular time is raised slightly by reason of the engagement of the pin 127 with the laterally extending portion 153 of the slide bar 149. When the bar drops over the foot portion 154 which enters the recess 145, the notch 141 receives the pin 142 and the further shifting of the bar 140 to the rear moves the frame 105 so that the gear pinion 30 35 40 45 50 55 60 65 70 75 80 85 90 95 100 105 110 115 120 125 130 meshes with the driving gear 98 which will be driven in a counter clockwise direction causing the ironing members to be opened. This operation continues until the pin 128 engages under the laterally extending portion 153 of the slide bar 149 when the latter will be raised causing its lower foot-portion 155 to engage the lower edge of the bar 140 to the left of the recess 145, with the result that the bar 140 is raised and the pin 142 carried by the frame 105 is released from the recess 141 and the opening driving gear mechanism is thrown out of operation. This position of the parts remains until the operator shifts the bar 140 forward when the end of the bar at the recess 145 drops off of the foot portion 155 carried by the slide bar, when the pin 142 will engage in the slot 141 and the frame 105 will be shifted in a clockwise direction, bringing the closing gear pinion 104 into engagement with the driving gear 98 when the ironing members will be closed.

Having described my invention, I claim:—

1. In an ironing press, an internal bosom ironing member having an ironing surface co-extensive with the bosom and extending beyond the shoulder seams to a point coincident with a transverse line touching the rear curve of the neck band, means for pressing

the yoke of the shirt to this line, and an external bosom ironing member having a recess for the neck band and an ironing face co-extensive with the ironing surface of the internal ironing member.

2. In an ironing press, an internal bosom ironing member having a bosom ironing face, an internal yoke ironing member having a yoke ironing face, said ironing faces meeting at substantially a line corresponding to the shirt folding line and extending from the neck band across the shoulder, suitable external ironing members co-operating with the internal bosom ironing member and the internal yoke ironing member, mechanism for operating the several parts, and means for supplying a heating medium to the several parts.

3. In an ironing press, an internal ironing member having a substantially unbroken bosom ironing face and a yoke ironing face, said faces meeting at substantially a line corresponding to the folding line of a shirt or waist, an external bosom ironing member, a yoke ironing member, mechanism for operating the several parts, and means for supplying a heating medium to the several parts.

4. In an ironing press, an internal ironing member having a bosom ironing face and a yoke ironing face, said faces meeting to form substantially a folding line across the shoulders and touching the rear portion of the neck band, means upon the internal ironing member and engaging in the neck band for locating the shirt or waist upon the internal ironing member, an external bosom ironing member, a yoke ironing member, means for operating the several parts, and means for supplying a heating medium to the several parts.

5. In an ironing press, an internal ironing member having a bosom ironing face and a yoke ironing face, said faces meeting to form substantially a folding line across the shoulders and touching the rear portion of the neck band, a neck band former upon the internal ironing member and engaging in the neck band for locating the shirt or waist upon the internal ironing member, an external bosom ironing member, a yoke ironing member, means for operating the several parts, and means for supplying a heating medium to the several parts.

6. In an ironing press, an internal bosom ironing member having a neck band edge at one end conforming to the shoulder folding line of a shirt, a neck band former arranged upon the face of said internal bosom ironing member and having its back portion in alinement with the neck band edge of such member, an internal yoke ironing member extending from said edge, an external bosom ironing member, an external yoke ironing member, means for operating

the several parts, and means for supplying heat to the several parts.

7. In an ironing press, an internal ironing member having a bosom ironing surface 5 on one side and a yoke ironing surface on the other side, said surfaces being arranged at an angle to each other and meeting at a line, an external bosom ironing member, a yoke ironing member, a carriage supporting said member, a suitable support for said carriage, means for moving said carriage to bring said yoke ironer into and out of engagement with the yoke ironing surface, means for moving the external ironing member, and means for supplying a heating medium to the several parts.

8. In an ironing press, a frame, an internal ironing member having a bosom ironing surface, a yoke ironing surface, suitable 20 guides carried by the frame, a carriage, rollers mounted on said carriage and engaging said guides, a yoke ironer mounted on said carriage and adapted to engage the yoke ironing surface, means for shifting said 25 yoke ironing member into engagement with the yoke ironing surface, and means for holding said member yieldingly in engagement with said surface.

9. In an ironing press, a frame, an internal ironing member having a bosom ironing surface, a yoke ironing surface, suitable 30 guides carried by the frame, a carriage, rollers mounted on said carriage and engaging said guides, a hollow yoke ironing member 35 mounted on said carriage and adapted to engage the yoke ironing surface, means for shifting said yoke ironing member into engagement with the yoke ironing surface, means for holding said member yieldingly 40 in engagement with said surface, and means for supplying a heating medium to the cavity in said hollow yoke ironing member.

10. In an ironing press, a frame, an internal bosom ironing member, an external bosom ironing member, an ironing plate, 45 trunnions carried by said plate, bearing rods upon said trunnions, an operating shaft, socket members rigidly secured to said shaft and having openings therein for receiving said rods loosely, and means for 50 operating said shaft.

11. An ironing press comprising an internal bosom ironing member, an external bosom ironing member, means for applying heat thereto, mechanism for closing the 55 ironing members one upon the other, an ironing plate arranged between said members and provided with a button-strip ironing portion at substantially the center, suitable padding on each side thereof, and 60 means for operating the several parts.

12. In an ironing press, an external ironing member, an internal ironing member substantially straight on its longitudinal dimension and having a longitudinally disposed recess, padding arranged in said recess, and means for moving the two ironing members with respect to each other.

13. In an ironing press, an ironing member having a longitudinally disposed recess, 70 packing in said recess, surface plate portions extending over the ironing member from said recess, another ironing member, an ironing plate having a central longitudinal extension, and padding on each side 75 thereof, said central longitudinal extension being adapted to align with the strip of padding in the other ironing member.

In testimony whereof I affix my signature in presence of two witnesses as follows: 80

SOLOMON D. GUGGENHEIM.
